(57) **CLAIM**

The ornamental design for a display screen or portion thereof with an animated graphical user interface, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a first image in a sequence for a first embodiment of a display screen or portion thereof with an animated graphical user interface;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof; and

FIG. 11 is an eleventh image thereof.

FIG. 12 is a first image in a sequence for a second embodiment of a display screen or portion thereof with an animated graphical user interface;

FIG. 13 is a second image thereof;

FIG. 14 is a third image thereof;

FIG. 15 is a fourth image thereof;

FIG. 16 is a fifth image thereof;

FIG. 17 is a sixth image thereof;

FIG. 18 is a seventh image thereof;

FIG. 19 is an eighth image thereof; and

FIG. 20 is a ninth image thereof.

FIG. 21 is a first image in a sequence for a third embodiment of a display screen or portion thereof with an animated graphical user interface;

FIG. 22 is a second image thereof;

FIG. 23 is a third image thereof;

FIG. 24 is a fourth image thereof;

FIG. 25 is a fifth image thereof;

FIG. 26 is a sixth image thereof;

FIG. 27 is a seventh image thereof;

FIG. 28 is an eighth image thereof;

FIG. 29 is a ninth image thereof;

FIG. 30 is a tenth image thereof; and

FIG. 31 is an eleventh image thereof.

FIG. 32 is a first image in a sequence for a fourth embodiment of a display screen or portion thereof with an animated graphical user interface;

FIG. 33 is a second image thereof;

FIG. 34 is a third image thereof;

(Continued)

FIG. 35 is a fourth image thereof;
 FIG. 36 is a fifth image thereof;
 FIG. 37 is a sixth image thereof;
 FIG. 38 is a seventh image thereof;
 FIG. 39 is an eighth image thereof; and,
 FIG. 40 is a ninth image thereof.

The appearance of the animated graphical user interface sequentially transitions between the images shown in FIGS. 1-11 according to the first embodiment, the images shown in FIGS. 12-20 according to the second embodiment, the images shown in FIGS. 23-31 according to the third embodiment, and the images shown in FIGS. 32-40 according to the fourth embodiment.

The process or period in which one image transitions to another forms no part of the claimed design.

The outermost broken line rectangle in the drawings shows a display screen or portion thereof and forms no part of the claimed design.
